MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONE-EXCHANGE SYSTEM.

1,116,540.

Specification of Letters Patent.

Patented Nov. 10, 1914.

Application filed August 10, 1912. Serial No. 714,421.

To all whom it may concern:

Be it known that I, MORTON L. JOHNSON, citizen of the United States, residing at Chicago, in the county of Cook and State of Illinois, have invented a certain new and 5 useful Improvement in Telephone-Exchange Systems, of which the following is a full, clear, concise, and exact description, reference being had to the accompanying drawings, forming a part of this specification.

My invention relates to telephone exchange systems employing operators for receiving calls and other operators for extending calling lines.

15 In practising my invention, the receiving operators have equipment whereby talking devices that are adapted to announce the designations of desired extensions of calling lines may be associated with the telephone 20 lines that extend between the two classes of operators whereby the telephone line extending or switching operators are automatically supplied with the necessary information.

25 As I have embodied my invention the extensions of the calling lines whose designations are to be announced are subscribers' lines though it is obvious that the invention is not to be limited to this characteristic.

30 Where the designations are numerical there are preferably ten talking devices adapted respectively to speak the digits 1, 2, 3, 4, 5, 6, 7, 8, 9 and the character 0, each talking device preferably speaking the name of but

35 one digit in the character. If the desired line is, for example, numbered 91, the talking device that speaks the digit nine and the talking device that speaks the digit one are, in the order named, successively

40 brought into association with the telephone line extending between the two operators that are employed in establishing the connection whereby the final or trunk operator is automatically informed of the number of

45 the desired line, the receiving operator, in the embodiment of the invention illustrated, not being required to speak the number, the receiving operator being relieved of this duty owing to the preferred form of talk-

50 ing device which I employ though I do not wish to be limited to this characteristic of the invention. When the connecting or trunk operator, the final operator, responds to the instructions thus automatically con-

55veyed to her she dissociates the employed

talking device or devices from the inter-operator telephone line. The telephone lines that extend between the operators are desirably the same trunk lines which are employed in connecting calling and called lines 60 though obviously the invention is not to be limited to this double use of such trunk lines.

In a connection which is being established the talking device or apparatus is coupled 65 with the link or trunk line that is being handled by the second or connecting operator so that when this operator hears the record that informs her of the number of the desired line she will employ the link coupled with the talking device and effect its connection with the desired line so that she need not be informed by the first or receiving operator either of the number of the calling line or the number of the link to be 70 employed. The link connectors desirably convey the recorded speech but the invention is not to be limited to this manner of coupling the talking equipment and link connectors. This feature of the invention 75 is broadly claimed irrespective of the nature of the talking equipment and the place at which the talking equipment is prepared to speak the designations of the wanted lines.

I will explain my invention more fully 80 by reference to the accompanying drawings showing one embodiment thereof to which the invention obviously is not to be limited and in which drawings—

Figures 1, 2 and 3, taken collectively in 85 numerical order, represent a telephone exchange system equipped in accordance with the invention, and Fig. 4 is a detail of a mechanical structure that may enter into some of the equipment.

In the drawings I have shown my invention as being embodied in a system coming within the scope of the application of Elmer R. Corwin, Serial No. 503,345, filed June 21, 1909, though of course the invention is not to be restricted to such a system.

I have illustrated two subscribers' stations (numbered for the sake of illustration as A³¹ and C³⁴) each having well known equipment that includes a telephone receiver switch hook 1 that engages a normal contact when supporting the associate telephone receiver 2 for the purpose of including a signal bell 3 and a condenser 4 in bridge of the associate telephone line, each 105 110

switch hook having an alternate contact engaged thereby when free of the telephone receiver to establish a metallic bridge between the sides of the associate line through the telephone receiver and transmitter 5.

When a subscriber, say at station A³¹, desires communication with another subscriber, say station C³⁴, the calling subscriber will remove his telephone receiver from its switch hook and metallically connect the line sides at his station whereby a circuit is established which may be traced from the upper grounded coil of the line relay 6, the upper intermediate armature switch of the switching relay 7 and its normal contact, the upper armature switch of the cutoff relay 8 and its normal contact, one side of the calling line, the telephone bridge of the calling line, the other side of the calling line, the lower armature switch cutoff relay 8 and its normal contact, the lower intermediate armature switch of relay 7 and its normal contact, the lower coil of the relay 6 to the grounded battery 9.

The armature switches of relay 6 are now attracted. A circuit is established which may be traced from the lower grounded armature switch of relay 6 and its alternate contact, the sluggishly operating interrupter relay 10, the motor magnet 11, the side switch wiper 12 in its first position, to the grounded common battery 9. The motor magnet 11 thereupon steps the wipers 13, 14, 15, 16, 17, 18 and 18¹ around until the wiper 15 encounters an ungrounded waiting contact whereupon the private relay 19 (which was previously included in circuit upon the initial operation of the motor magnet 11) is deenergized to cause the side switch wipers 12 and 20 to be moved to their second positions, the wiper 12 in its second position opening the circuit of the motor magnet 11 to arrest the wipers 13 to 18¹, inclusive. When the wiper 20 is in its second position it engages a grounded contact to ground the wiper 15 and the contact then engaged thereby and the other contacts of the other switches in multiple with the contact then engaged by the wiper 15 so that the wipers of other switches cannot stop with the wipers 15 thereof in engagement with the contacts in multiple with the grounded wiper 15 whereby other calling lines cannot become electrically connected or associated with those waiting contacts which have been appropriated by the wipers of a switch of a calling line, it being understood that the waiting contacts of each of the wipers 13 to 18¹ inclusive, are in multiple connection with the waiting contacts of similar wipers of other selector switches, in the system illustrated. In the system illustrated the selector switches are shown as being individual to the lines though the invention is not to be thus restricted, nor

in fact, is the invention to be restricted to systems which employ selector switches.

When the wipers of the selector switch actuated by a calling subscriber have been brought to rest with the wiper 15 in engagement with an ungrounded waiting contact, the calling line is automatically extended into connection with telephone conductors leading to a telephone outfit at the position of an idle operator, it being understood that the telephone conductors leading from several operators' positions are provided with multiply related terminals that are distributed among the selector switches whereby calling subscribers may automatically select the telephone conductors leading to idle operators. The selector switches may therefore be termed operator selector switches. The wipers 13 and 14 of the actuated operator selector switch are shown as being ones that are serially included in the telephonic circuit extending between the calling subscriber and the operator's telephone equipment 21, which equipment was selected because it was free for selection, and which cannot be selected while still in connection with the calling subscriber's line owing to a grounding of the contact then engaged by the wiper 15 of the employed selector switch. The calling party now informs the receiving operator of the number or designation of the desired line.

Assuming, as the drawings show, that the stations to be connected are subscribers' stations, then the switching devices which the operator employs are provided with numerical designations to guide the operators. As the system is illustrated, each telephone line is provided with a selector switch such as is illustrated at A, and which becomes connected with the calling line in a later stage of the process of connecting calling and called lines. This selector switch A is employed for selecting an idle manually controlled plug ended link connector B to which the invention is not to be limited. The receiving operators are, in the present case, each individually provided with a plurality of sets of switching devices, each set comprising three groups of buttons arranged, as illustrated, in three vertical rows, ten buttons to a row, the buttons in each row being numbered, consecutively from the top down, 1, 2, 3, 4, 5, 6, 7, 8, 9, 0. The buttons in the first vertical row C (reading from the left to the right) are employed for selecting an idle link connector B in the group of such connectors extending to the trunk operator having access to the line desired by the calling party.

The buttons in the second vertical row D are for associating any of the talking devices with the trunk lines, the buttons in the third vertical row E serving to associate

any of the talking devices with the trunk lines successively to the talking devices associated with the trunk lines by the buttons in the row D, there being as many of these 5 rows as the capacity and nature of the system requires, a limited number of rows D, E being illustrated for the sake of simplicity, the assumption being that each switch A is adapted to have its wipers placed in ten 10 different levels having ten sets of waiting contacts per level, these waiting contacts constituting terminals of link connectors, the waiting contacts in each level belonging to link connectors extending to a particular 15 operator's position or a plurality of such positions at a given board, or all of the link connectors extending from all of the waiting contacts of the different levels, though the link connectors may be otherwise apportioned for differing systems. Assuming that 20 the levels of waiting contacts of the selector switches A belong to link connectors extending to different exchanges or groups of lines, the operator will depress one of the 25 buttons in the row C that will bring the wipers of the selector switch A to the level of waiting contacts from which trunk lines extend to the desired exchange. Assuming that station C³⁴ is the desired line in the 30 desired exchange and that the link connectors extending from this exchange to the selector switches A have waiting contacts in the third levels of such switches, the operator will depress the third button from the 35 top in row C, the third button from the top in the second vertical row D, and the fourth button from the top in the third vertical row E, the buttons in each row being numbered from the top to the bottom successively whereafter the operator will depress 40 the starting key 22, the previously depressed buttons remaining depressed (though the key 22 is released immediately after its operation) for a sufficient period of time to permit 45 the trunk operator to establish the connection. Fig. 4 shows three adjacent keys in one row, C, D or E, one key being in a depressed position, the arrangement being such that when another key in the same 50 row is depressed the previously depressed key is restored by the shifting of the bar *a*, this mechanical construction being commonly known in the art. Each row of keys is provided with the equipment illustrated 55 in Fig. 4. After the desired buttons in the rows C, D, E have been depressed the starting key 22 is depressed, a circuit being thereby established through the relay 23, this relay 23 establishing a locking circuit through 60 itself in order that key 22 may be released, which locking circuit includes the winding of relay 23, its right hand armature switch, the left hand armature switch of relay 24, the wiper 15, side switch wiper 20 in second 65 position, to ground. The left hand armature switch of relay 23 is attracted to establish a circuit fraction which may be traced from the grounded common battery 9 through this left hand armature switch and its contact, the winding of a relay 25, the 70 left hand armature switch of such relay, the normal follow up contact of such armature switch to the starting brush 26. The brush 26 is electrically connected with a disk 27 once in each revolution 75 of such disk, this disk having a finger 28 adapted for contact with the brush 26 of limited duration. The disk 27 is grounded and may occupy approximately a second of time for a single revolution, the disk being 80 mounted upon a shaft 29 that is constantly driven by a motor 30, there being speed reduction gearing 31 interposed between the motor and the shaft. When the brush 26 is grounded upon engagement of the finger 85 28 circuit for the relay 25 which was partially traced is completed whereupon the left hand armature switch of such relay engages its alternate grounded contact to lock the circuit for the relay when the finger 90 28 has passed out of engagement with the brush 26. The intermediate armature switch of the now energized relay 25 establishes a circuit which may be traced from its grounded contact, through said armature 95 switch, the right hand armature switch of relay 32, the winding of relay 33, to the grounded battery 9. The left hand armature switch of the now energized relay 33 completes the circuit previously partially 100 established by the selected, third, button from the top of the left hand vertical row of switching buttons. This circuit may be traced from the disk 34 which has three fingers 35 and which disk is grounded, the 105 brush 36 when engaging a finger 35, the depressed key in row C, the left hand armature switch of relay 33, the relay 37, to the grounded battery 9. The relay 37 is thus energized three times for the purpose of raising the wipers of switch A to their proper level. The upper armature switch of relay 37 is thus caused to leave its contact three times. The relay 37² is employed for the 110 purpose of restoring the operator's equipment to normal as will later appear. The circuit that includes the upper armature switch of relay 37 also includes the two intermediate armature switches of relay 39, this relay 39 having been included in circuit when the side switch wiper 12 was put into second position. 115

The wipers of the employed selector switch A having been raised to their proper level, are stepped around by the rotary magnet 85 until the wiper 78 engages an ungrounded waiting contact whereupon the private magnet 89, whose circuit was established upon initial operation of the rotary magnet, is deenergized, this private magnet 120 125 130

thereupon moving the side switch wipers 77, 77¹ and 87 to their third positions, these wipers having been brought to their second positions by the private magnet 89 when 5 sluggishly operating private control relay 90 in series with the vertical magnet 86 is deenergized, a result occurring when the wipers of the switch A have been brought to their proper level.

10 When the side switch wiper 87 is in its second position it establishes a circuit for the rotary magnet 85 and when it is in its third position it opens the circuit for the rotary magnet 85 to arrest the travel of the wipers 15 and closes circuit through the switching relay 88, circuit being traceable from the upper grounded armature switch of the sluggishly operating relay 91 (circuit through which relay 91 was established upon the initial energization of relay 38, the armature switches of relay 91 remaining attracted during the vibration of the armature of relay 38) the winding of relay 88, the side switch wiper 87 in its third position, to the 20 grounded battery 9. When the relay 88 is energized, the circuit for relay 38 is opened so that the circuit for relay 91 is consequently open. The ground previously established by the upper armature switch of relay 91 is now replaced by the ground established by the left hand armature switch of relay 92, the circuit of the relay 92 being established by the left hand armature switch of relay 93, the circuit of this relay 93 being 25 traceable from its grounded coil through the upper armature switch of relay 94 and its normal contact, the traveling wiper 95 of switch A, the upper armature switch of relay 88 and its alternate contact the upper 30 intermediate armature switch of relay 39, the wiper 17 of the operator selector switch belonging to the calling line A³¹, the upper armature switch of relay 37 and its contact, the polarized relay 37², the wiper 18 and its 35 engaged waiting contact, the lower intermediate armature switch of relay 39, the intermediate armature switch of relay 88 and its alternate contact, the traveling wiper 96 of the selector switch A, the lower armature 40 switch of relay 94 and its normal contact, the remaining winding of relay 93, to the grounded battery 9. An idle link connector B having been selected, circuit for a signal 45 97, located within view of the attending trunk operator and individual to the selected link connector, is established, this circuit being traceable from the grounded battery 9 through the intermediate armature switch of relay 93, the signal 97, the intermediate 50 armature switch of relay 98 and its normal contact to ground.

When the wiper 78 and its associates are raised to their proper level, and before or during their travel in this level, the finger 55 47 upon disk 48 engages the brush 49 before

the shaft 29 has made a complete revolution. Owing to the engagement of the elements 47 and 49 circuit is established for the relay 32, which circuit includes the grounded disk 48, the finger 47, the brush 49, the left hand armature switch of relay 32 and its normal follow-up contact, the winding of relay 32, the right hand armature switch of relay 25 and the grounded battery 9. The relay 32 establishes a locking circuit for itself which 75 is traceable from the grounded alternate contact of the left hand armature switch, said armature switch, said relay 32, the right hand armature switch of relay 25, to the grounded battery. When the relay 32 is 80 energized circuit for relay 33 is broken at the right hand armature switch of relay 32. Circuit for the relay 37 is now opened at the left hand armature switch of relay 33, the relays 38 and 93 then being no longer 85 subject to the control of relay 37. Sluggishly operating relay 50 companion to relay 33 was energized upon the energization of relay 33 by way of the alternate contact of the right hand grounded armature switch 90 of relay 33. When the relay 33 is deenergized, as has been described, the still retained armature switch of relay 50 and the released right hand armature switch of relay 33 establish a circuit for the relay 24. 95 When relay 24 is operated its left hand armature switch establishes a locking circuit for the relay 24 which is traceable from the grounded battery 9, the winding of relay 24, the left hand armature switch of this relay 100 and its alternate contact, the wiper 15 and its engaged waiting contact, the side switch wiper 20 in its second position, to the grounded waiting contact previously engaged by the wiper 20. The energized relay 24 opens circuit, at its left hand armature switch, for the relay 23 to restore this 105 relay 23 to normal, the relays 25 and 32 being consequently restored to normal. The intermediate armature switches of relay 24, 110 that are serially related to the selected telephone 21, are now moved to disconnect the selected telephone 21 from circuit with the calling line.

Where a plurality of sets of keys, each set including a number of rows C, D, E, is employed a signal 99 is made individual to each of such sets and is governed by the associate relay 24, there being one relay 24 individual to each of such sets. When a set 115 of such keys C, D, E is selectively associated with the calling line by the selector switch, the corresponding signal 99 is included in a circuit that contains the grounded battery 9, the signal device (a lamp) 99, the right hand armature switch of relay 24, then deenergized, the wiper 15, the side switch wiper 20 in its second position, and the grounded button then engaged by the wiper 20. When the relay 24 is energized as has 120 125 130

just been described the circuit for the signal device 99 associated therewith is opened at the right hand armature switch of relay 24. The operator selector switch is not yet restored to normal but when it does later become restored to normal its wiper 15 removes the ground from the left hand armature switch of relay 24 to open the circuit of relay 24 and restore such relay to normal, the signal 99 being prevented from reconnection in circuit owing to the gap established at the wiper 15 when restored to normal. In this way all the equipment in association with the row of buttons C is restored to normal.

It has been described how the disk 34 with its three fingers 35 serves to step the wipers of the link selector A to the third level. The disk next to the left of disk 34, having but two contact fingers, will serve to bring these wipers to their second level and the next disk upon the left will serve to bring these wipers to their first level. The seven disks located in immediate succession upon the right of the disk 34 will serve, respectively, to bring these wipers to fourth level, fifth level, sixth level, seventh level, eighth level, ninth level and tenth level.

The signal 97 having been displayed, as previously described, the trunk operator manipulates her key e to bridge her telephone set f across the sides g h of the selected trunk line. The buttons in the rows D, E corresponding to the digit three and the digit four of the called subscriber's number having been depressed previously to the operation of the starting key 22, the trunk operator, having depressed her key e, is informed by the talking devices which the receiving operator has associated with the trunk line of the number of the desired line, C³⁴. When the key e is depressed circuit is established for the relay i that includes a grounded battery 9, said relay i, the side switch wiper 77¹ of the employed selector switch A, the wiper 96¹ of this switch A and the two lower contacts of the switch e, the bottom one of which is grounded. When relay i is energized a circuit is established which is traceable from its left hand grounded armature switch, the lowermost armature switch of relay 39, the wiper 18¹ and its then engaged waiting contact, the relay k, to the grounded battery 9. When the relay k is energized a circuit is established that includes the grounded battery 9, the armature switch of relay l, the armature switch of relay k and its then engaged contact, relay 51, its left hand armature switch and the normal follow-up contact thereof, the brush 26, the finger 28 when engaging the brush 26, and the grounded disk 27. When the relay 51 is energized it establishes a circuit for relay 53 that is traceable from

the right hand armature switch of relay 51 and its grounded contact, the right hand armature switch of relay 52, the winding of relay 53, to the grounded battery 9. A single primary coil 40 in conjunction with a secondary coil 40¹ serves telephonically to associate the talking devices with the calling line and the link extension thereof, the secondary 40¹ being connected in bridge of the conductors leading to the wipers 13 and 14 by way of the waiting contacts then engaged by said wipers. The telephonic relation of the talking devices with the calling line extension B is not however completely established until the relay i is energized whereupon the right hand armature switches of this relay serve to bring the secondary coil 40¹ into parallel with the telephone equipment f at the link connector B.

In my co-pending application Serial No. 709,427, filed July 15, 1912, I have disclosed a secondary such as 40¹ for associating the talking devices with the calling line so that the calling party would have the number of the desired line automatically conveyed to him, and certain claims relating to this characteristic of the system are included in my said co-pending application. When relay 53 is energized circuit for the primary 40 is established which is traceable from the primary, which is grounded, the left hand armature switch of relay 53, the button in the row D that has been depressed (in this instance the third button from the top) to the particular secondary coil 41 that is brought into association with the primary 40 by the depressed button. Each of the buttons of the two rows D E is associated with a secondary coil 41 and each secondary coil 41 is individual to a talking device, the different individual talking devices being capable of speaking, in the system under discussion, each a different digit 1 to 9, inclusive, and the character 0. The first talking device, reading from the left, speaks the digit 1, the next the digit 2, the next (the one corresponding to the third and depressed button from the top of row D) the digit 3, the next (corresponding to the fourth button from the top of row E which has been depressed) the digit 4 and so on.

Each talking device includes a record 42 for reproducing the name of the digit the talking device is to speak. A needle 43 is provided for each record and which serves to convey the sound to the phonograph horn 44. Each phonograph horn 44 faces a transmitter 45, included in a local circuit in primary relation to the associate secondary coil 41. It will be understood that the talking devices are common to the two rows of keys D, E, and that two similarly numbered keys in the rows D, E, may be depressed to bring the same talking device successively twice into telephonic relation with the sec-

ondary coil 41 which is brought into connection with the primary 40 by the depressed similar keys in the rows D, E. After the first digit has been spoken and before the shaft 29 has completed a revolution the grounded disk 48 is brought into a circuit that includes this disk, the finger 47 thereof, the brush 49, the sluggishly operating relay 110, the left hand armature switch of relay 52 and its normal contact, the intermediate armature switch of relay 51, and the grounded battery 9. The relay 52 establishes a locking circuit for itself that is traceable from the alternate contact of its left hand armature switch grounded through resistance, said armature switch, the winding of relay 52, the intermediate armature switch of relay 51, to the grounded battery 9. Circuit for relay 53 is now opened at the right hand armature switch of relay 52, the circuit for the primary coil 40, and the first secondary coil 41 to be included in circuit for announcing the first digit, being consequently open. The primary coil 40, assuming that the called line has two digits as in the example chosen, is now established through the next secondary coil 41 which is employed to announce the second digit by reason of the circuit established by the released right hand armature switch of relay 53 and the still attracted armature switch of the sluggishly operating relay 63 whose circuit was previously established upon the energization of the relay 53. The circuit established by these two armature switches of relays 53 and 63 includes the normal follow-up contact of the left hand armature switch of relay 64, the armature switch of relay *k*, the armature switch of relay *l*, and the grounded battery 9. The relay 64 establishes a locking circuit for itself that is traceable from the grounded alternate contact of its left hand armature switch, said armature switch, the relay 64, the armature switch of relay *k*, and the armature switch of relay *l* to the grounded battery 9. The right hand armature switch of relay 64 now establishes a circuit that includes its grounded contact, the right hand armature switch of relay 65, the relay 66, and the grounded battery 9. The left hand armature switch of relay 66 establishes the connection of the primary 40 and the second secondary coil 41 that is employed to speak the second digit, in this instance the digit 4, the circuit including the primary 40, the left hand armature switch of relay 66, the contacts of the fourth button from the top of the row E, and the associate secondary grounded coil 41. Just before the shaft 29 finishes the revolution that caused the operation of the phonograph second to be employed, the grounded disk 48 is included in a circuit which may be traced from this disk through the finger 47 thereof, the brush 49, the contacts of the sluggishly

operating relay 110, the left hand armature switch of relay 65, and its normal follow-up contact, the intermediate armature switch of relay 64 to the grounded battery 9

Relay 65 establishes a locking circuit for itself which is traceable from the grounded alternate contact of the left hand armature switch of relay 65, the winding of the relay, the intermediate armature switch of relay 64, to the grounded battery 9. When the right hand armature switch of the relay 65 is attracted it opens the circuit for the relay 66, the second circuit for the primary 40 being now opened at the left hand armature switch of this relay 66. When the relay 66 was energized circuit for the sluggishly operating relay 76 was established thereby. When relay 66 is deenergized, circuit for the magnet *l* is established owing to the coöperation of the still attracted armature switch of relay 76 and the normally positioned right hand armature switch of relay 66. Relay *l* is now energized during the brief remaining interval of the attraction of the armature switch of relay 76 to open the circuit of the relays 51 and 64 which in turn open the circuits of relays 52 and 65, these latter four relays being restored to normal. If the button *e* at the selected link B still remains depressed the two digits will be again spoken by the phonographs that are successively telephonically related with the selected link connector by way of the primary 40, a result which is due to the continued energization of the magnet *k* and the deenergization of the magnet *l* all as will be understood from previous description. If the operator at B has heard the number of the desired line to her satisfaction she may release the key *e* so as to separate the bottom contacts and thereby open the circuit for the magnet *k* so as to prevent the operation of the relays 51 and 64. Having learned the desired number the operator may test with the plug *m* in the usual way and if the line desired is idle the operator will plug into a multiple jack of the desired line and will signal the desired station, all as will be well understood by those skilled in the art. I do not wish to limit myself to the use of a connecting plug however for completing the final stage in the connection between calling and called lines.

When the connecting plug *m* has been inserted into the jack of the desired line circuit is established through the relay 98 and the cutoff relay 8 of the desired line, this circuit being traceable from the grounded battery 9, the cutoff relay 8 of the desired line, the sleeve of the multiple jack that receives the plug *m* the heel of said plug, the relay 98, to ground. The two uppermost armature switches of relay 98 are attracted to close gaps in the talking sides of the selected trunk and to open the circuit of the

test relay the two lower armature switches are attracted, to efface the signal 97, and to close a gap in the circuit of the supervisory signals 97¹ and 97². The intermediate armature switch of relay 98 also establishes a circuit for the relay 94 to reverse the connections of the relay 93 with the talking sides of the trunk line and thereby the connections of the battery 9 with the talking sides of the 10 trunk line, the flow of current through the polarized relay 37² being now reversed to bring the armature of this polarized relay into circuit with the battery 9, the wiper 16, the upper armature switch of relay 39, the winding of relay 7, the side switch wiper 77 in its 15 third position, the wiper 78 and its then engaged contact, and the grounded left hand armature switch of relay 92 and its then engaged contact. When relay 7 is energized 20 it establishes a locking circuit for itself that includes the grounded battery 9, the lowermost armature switch of relay 7, the winding of this relay, the side switch wiper 77 in its third position, the wiper 78, and the 25 grounded armature switch of relay 92 or the alternate ground connection established by the lowermost armature switch of relay 98 when attracted, the relays of the equipment being placed under the control of the operator by the magnet 98 and the plug *m* when the plug is received in the jack so that 30 there will be no faulty operation due to the release of the magnet 92 by the calling subscriber. When relay 7 is operated its intermediate armature switches engage their alternate contacts and separate from their 35 normal contacts whereby the calling line sides are connected with the selected link connector B and the relay 6 is deenergized. 40 When the relay 6 is deenergized circuit is established through the release magnet 80 and the previously closed off normal switch 81. The release magnet 80 thereupon restores the wipers of the operator selector 45 switch to normal and in doing so the relay *k* is included in open circuit if the key *e* happens to remain depressed. Thus the phonographs are cut out of circuit relation with the trunk operator and the calling 50 subscriber irrespective of the position of the key *e*.

I do not consider it necessary to describe the remainder of the equipment illustrated and the link B as such is so well known 55 by those skilled in the art. The relay 93 of the link B is under the control of the calling subscriber while the relay 93¹ is under the control of the called subscriber. When the parties are through conversation the calling subscriber's supervisory signal 97¹ and the called subscriber's supervisory signal 97² are included in closed circuit, the receivers at the connecting stations having been replaced upon their switch hooks. When the 60 operator withdraws the plug *m* ground pre-

viously established by the lowermost armature switch of relay 98 is removed from the wiper 78 whereby the circuits of relays 88 and 7 are opened. Circuit for the release magnet 82 is thereupon established by the 70 lowermost armature switch of relay 88 through the previously closed off normal switch 82¹ and the lower armature switches of relays 38 and 91 whereby the wipers of the link selector switch A are restored to 75 normal. When the relay 7 is included in open circuit the line equipment of the calling line is restored to normal and when the plug *m* is withdrawn the line equipment of the called line is restored to normal.

I do not deem it necessary to describe more in detail the construction and circuit arrangement of the operator selector switch and the link selector switch A since the equipment illustrated will be familiar to 80 those skilled in the art, particularly when reference is had to British Patent 1298 of 1910 and to *Van Deventer's "Telephonology,"* page 530.

I have shown, at the lower portion of Fig. 90 2, an operator selector switch and a link selector switch A peculiar to line C³⁴ and I have also illustrated another link connector B at the bottom of Fig. 3. Similar parts of these equipments are given similar characters of reference.

Attention is called to the relative location of the contact fingers projecting from the disk upon the shaft 29 which are so relatively located that the operations which 100 they govern will occur in proper order and sequence. There need be but one shaft 29 with the disks thereon for an entire exchange, the brushes bearing upon the disk being common to similarly related buttons 105 of the groups C, D, E distributed among the receiving operators.

It will be understood that the link connectors B may extend from receiving operators' positions (the positions of A operators) to trunking operators' positions (the positions of B operators) whether such positions are located in the same building or in different and widely separated buildings. It is considered that the lines extending to 115 these operators' positions extend to the same exchange irrespective of the proximity or separation of the A and B operators' positions.

I have hitherto devised a system wherein 120 talking devices have been employed at an exchange for announcing the designations of calling line extensions and this prior invention forms the subject matter of my co-pending application Serial No. 709,427, filed 125 July 15, 1912. In this said application I have disclosed a telephone exchange system including telephone lines extending to an exchange, link connectors at the exchange for uniting said lines, talking devices at the 130

exchange having speech reproducing record portions for speaking line designations, and operator controlled means for interchangeably coupling the talking devices with the link connectors while said link connectors are free to be taken for use and operated in effecting connection between calling and called lines, and the claims in the said co-pending application are broadly and specifically drawn to cover the invention contained in that system.

While I have herein shown and particularly described the preferred embodiment of my invention I do not wish to be limited to the precise details of construction and circuit arrangement shown as changes may readily be made without departing from the spirit of my invention.

Having thus described my invention I claim as new and desire to secure by Letters Patent the following:—

1. A telephone exchange system including telephone lines extending from telephone stations to different operators' positions at an exchange; telephone lines intervening between the operators' positions; talking devices at the exchange having reproducing record portions for speaking the designations of telephone line extensions, which extensions are to be supplied to calling lines; and means for enabling said talking devices to impress telephone currents upon the telephone lines intervening between the operators' positions.

2. A telephone exchange system including telephone lines extending from telephone stations to receiving operators' positions and from telephone stations to the positions of operators who take part in connecting calling and desired lines; telephone lines intervening between the first aforesaid operators' positions and the second aforesaid operators' positions; talking devices at the exchange having reproducing record portions for speaking the designations of telephone line extensions, which extensions are to be supplied to the calling lines; and means governed by the receiving operators for enabling said talking devices to impress telephonic currents upon the telephone lines intervening between said operators' positions.

3. A telephone exchange system including telephone lines extending from telephone stations to different operators' positions at an exchange; link connectors intervening between the operators' positions for inclusion in circuit between calling and desired lines and also constituting telephone lines intervening between the operators' positions; talking devices at the exchange having reproducing record portions for speaking the designations of telephone line extensions, which extensions are to be supplied to calling lines; and means for enabling said talking devices to impress telephonic cur-

rents upon the telephone lines intervening between the operators' positions.

4. A telephone exchange system including telephone lines extending from telephone stations to receiving operators' positions and from telephone stations to the positions of operators who take part in connecting calling and desired lines; link connectors intervening between the operators' positions for inclusion in circuit between calling and desired lines and also constituting telephone lines intervening between the operators' positions; talking devices at the exchange having reproducing record portions for speaking the designation of telephone line extensions, which extensions are to be supplied to the calling lines; and means governed by the receiving operators for enabling said talking devices to impress telephonic currents upon the telephone lines intervening between said operators' positions.

5. A telephone exchange system including telephone lines extending from telephone stations to different operators' positions at an exchange; telephone lines intervening between the operators' positions; talking devices at the exchange having reproducing record portions for speaking the designations of telephone line extensions, which extensions are to be supplied to calling lines; means for enabling said talking devices to impress telephonic currents upon the telephone lines intervening between the operators' positions; and means at the operators' positions between which telephone lines intervene for effecting connection between calling and desired lines.

6. A telephone exchange system including telephone lines extending from telephone stations to receiving operators' positions and from telephone stations to the positions of operators who take part in connecting calling and desired lines; telephone lines intervening between the first aforesaid operators' positions and the second aforesaid operators' positions; talking devices at the exchange having reproducing record portions for speaking the designations of telephone line extensions, which extensions are to be supplied to the calling lines; means governed by the receiving operators for enabling said talking devices to impress telephonic currents upon the telephone lines intervening between said operators' positions; and means at the operators' positions between which telephone lines intervene for effecting connection between calling and desired lines.

7. A telephone exchange system including telephone lines extending from telephone stations to different operators' positions at an exchange; telephone lines intervening between the operators' positions; a plurality of talking devices at the exchange

- having reproducing record portions for speaking differing portions of designations of telephone line extensions, which extensions are to be supplied to calling lines; and operator controlled means for enabling said talking devices successively to impress telephonic currents upon the telephone lines intervening between the operators' positions in arbitrarily determined order.

8. A telephone exchange system including telephone lines extending from telephone stations to receiving operators' positions and from telephone stations to the positions of operators who take part in connecting calling and desired lines; telephone lines intervening between the first aforesaid operators' positions and the second aforesaid operators' positions; a plurality of talking devices at the exchange having reproducing record portions for speaking differing portions of designations of telephone line extensions, which extensions are to be supplied to calling lines; and means governed by the receiving operators for enabling said talking devices successively to impress telephonic currents upon the telephone lines intervening between said operators' positions in arbitrarily determined order.

9. A telephone exchange system including telephone lines extending from telephone stations to different operators' positions at an exchange; link connectors intervening between the operators' positions for inclusion in circuit between calling and desired lines and also constituting telephone lines intervening between the operators' positions; a plurality of talking devices at the exchange having reproducing record portions for speaking differing portions of designations of telephone line extensions, which extensions are to be supplied to calling lines; and operator controlled means for enabling said talking devices successively to impress telephonic currents upon the telephone lines intervening between the operators' positions in arbitrarily determined order.

10. A telephone exchange system including telephone lines extending from telephone stations to receiving operators' positions and from telephone stations to the positions of operators who take part in connecting calling and desired lines; link connectors intervening between the operators' positions for inclusion in circuit between calling and desired lines and also constituting telephone lines intervening between the operators' positions; a plurality of talking devices at the exchange having reproducing record portions for speaking differing portions of designations of telephone line extensions, which extensions are to be supplied to calling lines; and means governed by the receiving operators for enabling said talking devices successively to impress telephonic currents upon the telephone lines intervening between the operators' positions in arbitrarily determined order.

11. A telephone exchange system including telephone lines extending from telephone stations to different operators' positions at an exchange; telephone lines intervening between the operators' positions; a plurality of talking devices at the exchange having reproducing record portions for speaking differing portions of designations of telephone line extensions, which extensions are to be supplied to calling lines; operator controlled means for enabling said talking devices successively to impress telephonic currents upon the telephone lines intervening between the operators' positions in arbitrarily determined order; and means at the operators' positions between which telephone lines intervene for effecting connection between calling and desired lines.

12. A telephone exchange system including telephone lines extending from telephone stations to receiving operators' positions and from telephone stations to the positions of operators who take part in connecting calling and desired lines; telephone lines intervening between the first aforesaid operators' positions and the second aforesaid operators' positions; a plurality of talking devices at the exchange having reproducing record portions for speaking differing portions of designations of telephone line extensions, which extensions are to be supplied to calling lines; means governed by the receiving operators for enabling said talking devices successively to impress telephonic currents upon the telephone lines intervening between said operators' positions in arbitrarily determined order; and means at the operators' positions between which telephone lines intervene for effecting connection between calling and desired lines.

13. A telephone exchange system including telephone lines extending from telephone stations to different operators' positions at an exchange; telephone lines intervening between the operators' positions; a plurality of talking devices at the exchange having records of differing import; and operator controlled means for causing said talking devices to effect the impression of telephonic current upon the telephone lines intervening between operators' positions in succession in arbitrarily determined order.

14. A telephone exchange system including telephone lines extending from telephone stations to receiving operators' positions and from telephone stations to the positions of operators who take part in connecting calling and desired lines; telephone lines intervening between the first aforesaid operators' positions and the second aforesaid operators' positions; a plurality of talking devices at the exchange having reproducing record portions for speaking differing portions of designations of telephone line extensions, which extensions are to be supplied to calling lines; and means governed by the receiving operators for enabling said talking devices successively to impress telephonic currents upon the telephone lines intervening between the operators' positions in arbitrarily determined order.

records of differing import; and means controlled by the receiving operators for causing said talking devices to effect the impression of telephonic current upon the telephone lines intervening between the operators' positions in succession in arbitrarily determined order.

15. A telephone exchange system including telephone lines extending from telephone stations to receiving operators' positions and from telephone stations to the positions of operators who take part in connecting calling and desired lines; link connectors intervening between the operators' positions for inclusion in circuit between calling and desired lines and also constituting telephone lines intervening between the operators' positions; a plurality of talking devices at the exchange having records of differing import; and means controlled by the receiving operators for causing said talking devices to effect the impression of telephonic current upon the telephone lines intervening between the operators' positions in succession in arbitrarily determined order.

16. A telephone exchange system including telephone lines extending from telephone stations to receiving operators' positions and from telephone stations to the positions of operators who take part in connecting calling and desired lines; telephone lines intervening between the first aforesaid operators' positions and the second aforesaid operators' positions; a plurality of talking devices at the exchange having records of differing import; means controlled by the receiving operators for causing said talking devices to effect the impression of telephonic current upon the telephone lines intervening between the operators' positions in succession in arbitrarily determined order; and means at the operators' positions between which telephone lines intervene for effecting connection between calling and desired lines.

17. A telephone exchange system including telephone lines extending from telephone stations to receiving and connecting operators' positions at an exchange; and talking devices having reproducing record portions for speaking the designations of telephone line extensions that are to be supplied to calling lines and which talking devices are within the control of the receiving operators and are provided with means for telephonic connection with connecting operators.

18. A telephone exchange system including telephone lines extending to call receiving and switching or connecting operators' positions; a link connector intervening between these positions; and talking equipment, coupled with the link connector, having speech reproducing record portions for

speaking the designations of calling line 65 extensions to switching operators.

19. A telephone exchange system including telephone lines extending to call receiving and switching or connecting operators' positions; link connectors intervening between these positions; and talking devices having speech reproducing record portions for speaking the designations of calling line 70 extensions to switching operators there being means for coupling employed link connectors with the talking devices used to speak the designations of calling line extensions.

20. A telephone exchange system including telephone lines extending to call receiving and switching or connecting operators' positions; link connectors intervening between these positions; and talking devices having speech reproducing record portions for speaking the designations of calling line 80 extensions to switching operators, there being means controlled by the receiving operators, for coupling employed link connectors with the talking devices used to speak the designations of calling line extensions.

21. A telephone exchange system including telephone lines extending to call receiving and switching or connecting operators' positions; a link connector intervening between these positions; and talking equipment having speech reproducing record portions 95 coupled with the link connector and prepared by the receiving operator for speaking the designations of calling line extensions to switching operators.

22. A telephone exchange system including telephone lines extending to call receiving and switching or connecting operators' positions; link connectors intervening between these positions; and talking devices 105 having speech reproducing record portions and prepared by the receiving operators for speaking the designations of calling line extensions to switching operators, there being means for coupling employed link connectors with the talking devices used to speak the designations of calling line extensions.

23. A telephone exchange system including telephone lines extending to call receiving and switching or connecting operators' positions; link connectors intervening between these positions; and talking devices having speech reproducing record portions and prepared by the receiving operators for 115 speaking the designations of calling line extensions to switching operators, there being means controlled by the receiving operators for coupling employed link connectors with the talking devices used to speak the designations of calling line extensions.

24. A telephone exchange system including telephone lines extending to call receiv-

ing and switching or connecting operators' positions; link connectors intervening between these positions; talking devices having speech reproducing record portions for speaking the designations of calling line extensions to switching operators; and means for interchangeably coupling the talking devices and link connectors.

25. A telephone exchange system including telephone lines extending to call receiving and switching or connecting operators' positions; link connectors intervening between these positions; talking devices having speech reproducing record portions for speaking the designations of calling line extensions to switching operators; and means controlled by the receiving operators for interchangeably coupling the talking devices and link connectors.

26. A telephone exchange system including telephone lines extending to call receiving and switching or connecting operators' positions; link connectors intervening between these positions; talking devices having speech reproducing record portions and prepared by the receiving operators for speaking the designations of calling line extensions to switching operators; and means for interchangeably coupling the talking devices and link connectors.

27. A telephone exchange system including telephone lines extending to call receiving and switching or connecting operators' positions; link connectors intervening between these positions; talking devices having speech reproducing record portions and prepared by the receiving operators for speaking the designations of calling line extensions to switching operators; and means controlled by the receiving operators for interchangeably coupling the talking devices and link connectors.

28. A telephone exchange system including telephone lines extending to call receiving and switching or connecting operators' positions at which are located link connectors for connecting calling and called lines; and talking equipment, coupled with the link connector connected with the calling line at the receiving operator's position, and having speech reproducing record portions for speaking the designations of calling line extensions to switching operators.

29. A telephone exchange system including telephone lines extending to call receiving and switching or connecting operators' positions at which are located link connectors for connecting calling and called lines; talking devices having speech reproducing record portions for speaking to the switching operators the designations of calling line extensions; and means for interchangeably coupling the talking devices and link connectors connected with calling lines at receiving operators' positions.

30. A telephone exchange system including telephone lines extending to call receiving and switching or connecting operators' positions at which are located link connectors for connecting calling and called lines; talking devices having speech reproducing record portions for speaking the designations of calling line extensions to switching operators; and means controlled by the receiving operators for interchangeably coupling the talking devices and link connectors connected with calling lines at the receiving operators' positions.

31. A telephone exchange system including telephone lines extending to call receiving and switching or connecting operators' positions at which are located link connectors for connecting calling and called lines; talking devices having speech reproducing record portions and prepared by the receiving operators for speaking the designations of calling line extensions to switching operators; and means for interchangeably coupling the talking devices and link connectors connected with calling lines at receiving operators' positions.

32. A telephone exchange system including telephone lines extending to call receiving and switching or connecting operators' positions at which are located link connectors for connecting calling and called lines; talking devices having speech reproducing record portions and prepared by the receiving operators for speaking the designations of calling line extensions to switching operators; and means controlled by the receiving operators for interchangeably coupling the talking devices and link connectors connected with calling lines at receiving operators' positions.

33. A telephone exchange system including telephone lines extending to call receiving and switching or connecting operators' positions; a link connector intervening between these positions; and talking equipment, having speech reproducing record portions telephonically coupled with the link connector, for speaking the designations of calling line extensions.

34. A telephone exchange system including telephone lines extending to call receiving and switching or connecting operators' positions; link connectors intervening between these positions; and talking devices having speech reproducing record portions for speaking the designations of calling line extensions, there being means for interchangeably and telephonically coupling link connectors with the talking devices used to speak the designations of calling line extensions.

35. A telephone exchange system including telephone lines extending to call receiving and switching or connecting operators' positions; talking equipment having speech

reproducing record portions for speaking the designations of calling line extensions to switching operators; and means governed by a receiving operator for bringing the speech reproducing portion of said equipment interchangeably into connection with the switching or connecting operators' positions.

36. A telephone exchange system including telephone lines extending to call receiving and switching or connecting operators' telephone equipments; talking equipment having speech reproducing record portions for speaking the designations of calling line extensions to switching operators; and means governed by a receiving operator for bringing the speech reproducing portion of said equipment interchangeably into connection with the switching or connecting operators' telephone equipments.

37. A telephone exchange system including telephone lines extending to call receiving and switching or connecting operators' positions; talking equipment having speech reproducing record portions and prepared by receiving operators for speaking the designations of calling line extensions to switching operators; and means governed by a receiving operator for bringing the speech reproducing portion of said equipment interchangeably into connection with the switching or connecting operators' positions.

38. A telephone exchange system including telephone lines extending to call receiving and switching or connecting operators' telephone equipments; talking equipment having speech reproducing record portions and prepared by receiving operators for speaking the designations of calling line extensions to switching operators; and means governed by a receiving operator for bringing the speech reproducing portion of said equipment interchangeably into connection with the switching or connecting operators' telephone equipments.

39. A telephone exchange system including telephone lines extending to call receiving and switching or connecting operators' positions; talking equipment having speech reproducing record portions for speaking the designations of calling line extensions to switching operators; and link connectors for extending calling lines and interchangeably associated with the switching or connecting operators' positions by a receiving operator and serving to convey the record reproductions to the selected switching operator.

40. A telephone exchange system including telephone lines extending to call receiving and switching or connecting operators' positions; talking equipment having speech reproducing record portions and prepared by receiving operators for speaking the designations of calling line extensions to switching operators; and link connectors for ex-

tending calling lines and interchangeably associated with the switching or connecting operators' positions by a receiving operator and serving to convey the record reproductions to the selected switching operator.

41. A telephone exchange system including telephone lines extending to call receiving and switching or connecting operators' telephone equipments, talking equipment having speech reproducing record portions for speaking the designations of calling line extensions to switching operators; and link connectors for extending calling lines and interchangeably associated with switching or connecting operators' telephone equipments by a receiving operator and serving to convey the record reproductions to the telephone of the selected switching operator.

42. A telephone exchange system including telephone lines extending to call receiving and switching or connecting operators' telephone equipments; talking equipment having speech reproducing record portions and prepared by receiving operators for speaking the designations of calling line extensions to switching operators; and link connectors for extending calling lines and interchangeably associated with the switching or connecting operators' telephone equipments by a receiving operator and serving to convey the record reproductions to the telephone of the selected switching operator.

43. A telephone exchange system including telephone lines extending to call receiving and switching or connecting operators' positions and divided into groups for accessibility by the latter operators; talking equipment having speech reproducing record portions for speaking the designations of calling line extensions to switching operators; and means governed by a receiving operator for bringing the speech reproducing portion of said equipment interchangeably into connection with the switching or connecting operators' positions.

44. A telephone exchange system including telephone lines extending to call receiving and switching or connecting operators' telephone equipments and divided into groups for accessibility by the switching operators; talking equipment having speech reproducing record portions for speaking the designations of calling line extensions to switching operators; and means governed by a receiving operator for bringing the speech reproducing portion of said equipment interchangeably into connection with the switching or connecting operators' telephone equipments.

45. A telephone exchange system including telephone lines extending to call receiving and switching or connecting operators' positions and divided into groups for accessibility by the latter operators; talking equipment having speech reproducing record por-

tions and prepared by receiving operators for speaking the designations of calling line extensions to switching operators; and means governed by a receiving operator for bringing the speech reproducing portion of said equipment interchangeably into connection with the switching or connecting operators' positions.

46. A telephone exchange system including telephone lines extending to call receiving and switching or connecting operators' telephone equipments and divided into groups for accessibility by the switching operators; talking equipment having speech reproducing record portions and prepared by receiving operators for speaking the designations of calling line extensions to switching operators; and means governed by a receiving operator for bringing the speech reproducing portion of said equipment interchangeably into connection with the switching or connecting operators' telephone equipments.

47. A telephone exchange system including telephone lines extending to call receiving and switching or connecting operators' positions and divided into groups for accessibility by the latter operators; talking equipment having speech reproducing record portions for speaking the designations of calling line extensions to switching operators; and link connectors for extending calling lines and interchangeably associated with the switching or connecting operators' positions by a receiving operator and serving to convey the record reproductions to the selected switching operator.

48. A telephone exchange system including telephone lines extending to call receiving and switching or connecting operators' positions and divided into groups for accessibility by the latter operators; talking equipment having speech reproducing record portions and prepared by receiving operators for speaking the designations of calling line extensions to switching operators; and link connectors for extending calling lines and interchangeably associated with the switching or connecting operators' positions by a receiving operator and serving to convey the record reproductions to the selected switching operator.

49. A telephone exchange system including telephone lines extending to call receiving and switching or connecting operators' telephone equipments and divided into groups for accessibility by the switching operators; talking equipment having speech reproducing record portions for speaking 55 the designations of calling line extensions to switching operators; and link connectors for extending calling lines and interchangeably associated with switching or connecting operators' telephone equipments by a receiving operator and serving to convey the rec- 60 65

ord reproductions to the telephone of the selected switching operator.

50. A telephone exchange system including telephone lines extending to call receiving and switching or connecting operators' 70 telephone equipments and divided into groups for accessibility by the switching operators; talking equipment having speech reproducing record portions and prepared by receiving operators for speaking the designations of calling line extensions to switching operators; and link connectors for extending calling lines and interchangeably associated with the switching or connecting operators' telephone equipments by a receiving operator and serving to convey the record reproductions to the telephone of the selected switching operator. 75 80

51. A telephone exchange system including telephone lines extending to call receiving and switching or connecting operators' position and divided into groups for accessibility by the latter operators, there being a plurality of switching operators' positions for each group of telephone lines; talking equipment having speech reproducing record portions for speaking the designations of calling line extensions to switching operators; and means governed by a receiving operator for bringing the speech reproducing portion of said equipment interchangeably into connection with the switching or connecting operators' positions; said means including selector switches for selecting an idle operator in the group of positions containing wanted lines. 85 90 95 100

52. A telephone exchange system including telephone lines extending to call receiving and switching or connecting operators' telephone equipments and divided into groups for accessibility by the switching operators, there being a plurality of switching operators' telephone equipments for each group of telephone lines; talking equipment having speech reproducing record portions for speaking the designations of calling line extensions to switching operators; and means governed by a receiving operator for bringing the speech reproducing portion of said equipment interchangeably into connection with the switching or connecting operators' telephone equipments, said means including selector switches for selecting an idle operator in the group of telephone equipments containing wanted lines. 105 110 115 120

53. A telephone exchange system including telephone lines extending to call receiving and switching or connecting operators' positions and divided into groups for accessibility by the latter operators, there being a plurality of switching operators' positions for each group of telephone lines; talking equipment having speech reproducing record portions and prepared by receiving operators for speaking the designations 130 125

- of calling line extensions to switching operators; and means governed by a receiving operator for bringing the speech reproducing portion of said equipment interchangeably into connection with the switching or connecting operators' positions, said means including selector switches for selecting an idle operator in the group of positions containing wanted lines.

54. A telephone exchange system including telephone lines extending to call receiving and switching or connecting operators' telephone equipments and divided into groups for accessibility by the switching operators, there being a plurality of switching operators' telephone equipments for each group of telephone lines; talking equipment having speech reproducing record portions and prepared by receiving operators for speaking the designations of calling line extensions to switching operators; and means governed by a receiving operator for bringing the speech reproducing portion of said equipment interchangeably into connection with the switching or connecting operators' telephone equipments, said means including selector switches for selecting an idle operator in the group of telephone equipments containing wanted lines.

55. A telephone exchange system including telephone lines extending to call receiving and switching or connecting operators' positions and divided into groups for accessibility by the latter operators, there being a plurality of switching operators' positions for each group of telephone lines; talking equipment having speech reproducing record portions for speaking the designations of calling line extensions to switching operators; link connectors for extending calling lines and interchangeably associated with the switching or connecting operators' positions by a receiving operator and serving to convey the record reproductions to the selected switching operator; and selector switches for selecting an idle operator in the group of positions having access to wanted lines.

56. A telephone exchange system including telephone lines extending to call receiving and switching or connecting operators' positions and divided into groups for accessibility by the latter operators, there being a plurality of switching operators' positions for each group of telephone lines; talking equipment having speech reproducing record portions and prepared by receiving operators for speaking the designations of calling line extensions to switching operators; link connectors for extending calling lines and interchangeably associated with the switching or connecting operators' positions by a receiving operator and serving to convey the record reproductions to the selected switching operator; and selector switches for selecting an idle operator in the group of positions having access to wanted lines.

57. A telephone exchange system including telephone lines extending to call receiving and switching or connecting operators' telephone equipments and divided into groups for accessibility by the switching operators, there being a plurality of switching operator's telephone equipments for each group of telephone lines; talking equipment having speech reproducing record portions for speaking the designations of calling line extensions to switching operators; link connectors for extending calling lines and interchangeably associated with switching or connecting operators' telephone equipments by a receiving operator and serving to convey the record reproductions to the telephone of the selected switching operator; and selector switches for selecting an idle operator in the group of telephone equipments having access to wanted lines.

58. A telephone exchange system including telephone lines extending to call receiving and switching or connecting operators' telephone equipments and divided into groups for accessibility by the switching operators, there being a plurality of switching operators' telephone equipments for each group of telephone lines; talking equipment having speech reproducing record portions and prepared by receiving operators for speaking the designations of calling line extensions to switching operators; link connectors for extending calling lines and interchangeably associated with the switching or connecting operators' telephone equipments by a receiving operator and serving to convey the record reproductions to the telephone of the selected switching operator; and selector switches for selecting an idle operator in the group of telephone equipments having access to wanted lines.

59. A telephone exchange system including telephone lines extending to call receiving and switching or connecting operators' positions and divided into groups for accessibility by the latter operators, there being a plurality of switching operators' positions for each group of telephone lines; talking equipment having speech reproducing record portions for speaking the designations of calling line extensions to switching operators; link connectors for extending calling lines and interchangeably associated with the switching or connecting operators' positions by a receiving operator and serving to convey the record reproductions to the selected switching operator; link connectors at the switching or connecting operators' positions for connecting desired lines with calling lines; and selector switches

for selecting idle ones of the latter link connectors and connecting the same with the former link connectors.

60. A telephone exchange system including telephone lines extending to call receiving and switching or connecting operators' positions and divided into groups for accessibility by the latter operators, there being a plurality of switching operators' positions 5 for each group of telephone lines; talking equipment having speech reproducing record portions and prepared by receiving operators for speaking the designations of calling line extensions to switching operators; link connectors for extending calling lines and interchangeably associated with the switching or connecting operators' positions by a receiving operator and serving to convey the record reproductions to the selected 10 switching operator; link connectors at the switching or connecting operators' positions for connecting desired lines with calling lines; and selector switches for selecting idle ones of the latter link connectors and connecting the same with the former link connectors.

61. A telephone exchange system including telephone lines extending to call receiving and switching or connecting operators' 15 telephone equipments and divided into groups for accessibility by the switching operators, there being a plurality of switching operators' telephone equipments for each group of telephone lines; talking equipment 20 having speech reproducing record portions for speaking the designations of calling line extensions to switching operators; link connectors for extending calling lines and interchangeably associated with switching or 25 connecting operators' telephone equipments by a receiving operator and serving to convey the record reproductions to the telephone of the selected switching operator; link connectors at the switching or connecting 30 operators' telephone equipments for connecting desired lines with calling lines; and selector switches for selecting idle ones of the latter link connectors and connecting the same with the former link connectors.

62. A telephone exchange system including telephone lines extending to call receiving and switching or connecting operators' 35 telephone equipments and divided into groups for accessibility by the switching operators; there being a plurality of switching 40 operators' telephone equipments for each group of telephone lines; talking equipment 45 having speech reproducing record portions

and prepared by receiving operators for speaking the designations of calling line extensions to switching operators; link connectors for extending calling lines and interchangeably associated with the switching or connecting operators' telephone equipments by a receiving operator and serving to 50 convey the record reproductions to the telephone of the selected switching operator; link connectors at the switching or connecting operators' telephone equipments for connecting desired lines with calling lines; and selector switches for selecting idle ones of the latter link connectors and connecting the same with the former link connectors.

63. A telephone exchange system including telephone lines extending to switching or connecting operators' positions; talking devices having speech reproducing record portions for reproducing the designations of wanted lines; telephone conductors intervening between said devices and the switching operators' positions; and selector switching mechanism for connecting the speech reproducing portions of said talking devices with said telephone conductors.

64. A telephone exchange system including telephone lines extending to switching or connecting operators' positions; talking devices having speech reproducing record portions prepared by receiving operators for reproducing the designations of wanted 5 lines; telephone conductors intervening between said devices and the switching operators' positions; and selector switching mechanism for connecting the speech reproducing portions of said talking devices with said 10 telephone conductors.

65. A telephone exchange system including telephone lines extending to receiving and switching or connecting operators' positions; link connectors intervening between 100 receiving and switching operators' positions and interchangeably associated with the latter positions by a receiving operator; and talking devices having speech reproducing record portions and provided with means 105 for coupling said reproducing record portions with the link connectors for transferring recorded speech by the link connectors to selected switching operators.

In witness whereof, I hereunto subscribe 110 my name this third day of August A. D., 1912.

MORTON L. JOHNSON.
